(57) **CLAIM**

The ornamental design for a styling wand, as shown and described.

DESCRIPTION

FIG. 1 is a perspective view of the styling wand;
FIG. 2 is a left side elevational open view thereof;
FIG. 3 is a right side elevational closed view thereof;
FIG. 4 is a front elevational view thereof;
FIG. 5 is a rear elevational view thereof;
FIG. 6 is a top plan view thereof; and,
FIG. 7 is a bottom plan view thereof of the present invention.
The broken lines are shown to illustrate unclaimed environmental structure and form no part of the claimed design.
